SHEET-SPACING MACHINE

Charles F. Pflanze, University City, Mo.

Application July 27, 1939, Serial No. 286,737

15 Claims. (Cl. 271—1)

This invention presents new and useful improvements in sheet-spacing machines of the type used for separating stacked or piled sheets or blanks and forwarding them in a regularly predetermined, overlapped, spaced relationship for printing, glueing, stamping, or the like. More specifically, this invention comprises a simplified form of rotary sheet-spacing mechanism, in which a pile of sheets are removably supported in a holder and whereby the forward end of the lowermost sheet is adapted to be seized upon its underside by means of an oscillatory suction arm and lowered into the bights formed by a pair of upper, laterally spaced, roller segments with a lower, single, elongated roller. The machine desirably includes a pair of intermediate, rotary, separator disks and reciprocatory stop pins serving to separate and retain the successive upper sheets until seized by the suction arm. The sheets, upon being brought down into the bight of the upper roller segments and the lower roller, are by means of the rotary frictional contact therebetween forced forwardly onto spacing and conveyor belts, which tend to advance the overlapped sheets away from the rollers. A forwardly extended spacing arm, having an aligned, adjustably depended surface guide strip, is pivotally mounted upon the upper rear portion of the machine and is spring set so as to be normally forced downwardly upon one of the aforementioned belts. A roller is adjustably depended from the spacing arm freely astride the depended guide strip so as to be rotated by the central spacing belt. As the sheets are moved forwardly onto the belts, being guided thereon by the guide strip, they pass beneath the before-mentioned rollers whereby the sheets are spaced in a regular overlapped relationship thereto, this spacing, or calibration, being retained by means of additional conveyor belts coming into contact with the surface of the sheets. The spacing of the sheets is governed by the speed of the aforementioned belts.

In general, this invention has for its object to eliminate the objectionable "Geneva" or reciprocatory type of intermittent movement as commonly employed in this type of machine, and to substitute therefor a true rotary motion for feeding the blanks into the spacing device, thereby reducing the wear and vibration of the various parts of the machine. This, quite naturally, increases the efficiency of the machine and speeds up production, and assures a higher degree of

accuracy of the machine at a materially increased speed of operation.

Another feature of this invention is to provide a constant driving system for the spacing and conveyor belts wherein all the belts are caused to travel at the same constant rate of speed, and in which is employed a pair of external gears which may be easily and rapidly changed so as to increase or decrease the belt speed, thereby increasing or decreasing the spacing of the blanks.

It is an important object of the present invention to provide an apparatus for arranging and advancing sheets in fanned out relation which comprises, in combination, a support for a stack of sheets, roller mechanism comprising opposed rotary members for intermittently gripping sheets between them to advance the sheets step by step, means for periodically placing the leading margins of the sheets from the stack one after another in the space between the rotary members, subsequently acting mechanism for engaging and advancing each sheet only after it has been advanced through a plurality of steps by the roller mechanism, and means for holding stationary during a period when the rotary members are out of sheet gripping relation to one another, a partially advanced sheet between the rotary members which has become disengaged from the stack and which would otherwise be uncontrolled in such period.

With the foregoing and such other objects in view as will later appear in the specification, reference will be had to the accompanying drawings wherein:

Fig. 1 is a side view of the machine as viewed from the operator's position, this being the side of the machine on which the operator positions himself, and as here shown the successive machines and connecting belts have been removed.

Fig. 2 is a side view of the machine as viewed from the opposite side of Fig. 1, a motor drive being here shown.

Fig. 3 is a partial vertical sectional view of the machine as viewed in Fig. 2.

Fig. 4 is a partial angular, top view, partly in section, of the head of the machine, showing the feeding mechanism.

Fig. 5 is a partial top view, partly in section, of the head of the machine, showing the spacing mechanism.

Fig. 6 is an enlarged, vertical, medial, sectional view through the upper part of the machine as viewed from the side.

Fig. 7 is an enlarged, perspective view of the fixed type of segmental roller as shown on the machine.

Fig. 8 is an enlarged, partial longitudinal, sectional view of the spacing device.

Fig. 9 is an enlarged, fragmentary, sectional view of the upper end of the blank holder, showing the threaded suction connection thereto.

Fig. 10 is an enlarged, fragmentary, sectional view of an adjustable type suction connection as shown in Fig. 9.

Fig. 11 is an enlarged top view of the upper end of the blank holder, showing the adjustable form of suction connection thereto.

Fig. 12 is an enlarged, diagrammatic view of some of the principal inventive features of the invention.

Fig. 13 is an enlarged, perspective view of an adjustable type segmental roller.

Fig. 14 is an enlarged, transverse, sectional view of the ratchet blank holder, the outer end of the oscillatory suction arm being shown therebelow.

Fig. 15 is an enlarged, fragmentary, sectional view of the reciprocatory stop pin cam and arm that operates in synchronization with the separator disks.

Fig. 16 is an enlarged, partial rear view of the suction arm, actuating cam, and follower mechanism.

Fig. 17 is a side view of Fig. 16.

Referring now more particularly to the drawings, it will be seen that they illustrate an envelope spacing machine A, in which are embodied my inventive features, this type of machine being shown merely for the purpose of exemplification.

As here shown, the machine comprises, in general, a pair of base or mounting frames B and a head frame C. A power shaft 18 is transversely journaled through the rear, vertical portion 19 of the base frames near the bottom thereof and, as here shown, is connected to a motor drive 20 by means of a belt 21 whereby the power shaft is supplied with motive power. A sprocket gear 22, rigidly mounted upon the power shaft, is connected by a sprocket chain 23 to a similar sprocket gear 24 keyed to a shaft 25 journaled through the front, lower part of the head C, both of the aforementioned sprocket gears being positioned within the frame of the machine at one side thereof. A spur gear 26, in juxtaposition with the sprocket gear 24 upon the shaft 25 and adapted to be driven in unison therewith, is provided for driving a gear 27 mounted upon a shaft 28. This shaft 28 has a sprocket gear 29 secured upon its outer end externally of the frame on the operator's side of the machine. A similar sprocket gear 30, secured upon a shaft 31 journaled transversely the head, is adapted to be driven by the gear 29 by means of a connecting sprocket chain 32. An elongated roller 33, medially positioned within the head upon the shaft 31, is provided and is adapted to be rotated at a uniform rate of speed by the sprocket 30, the function of which will be later explained.

A pair of spaced segmental rollers 34 are provided in vertical alignment with, above, and in resilient contact with the aforementioned cylindrical roller 33, and are rigidly mounted upon independent horizontal stub shafts 35. These segmental rollers, each comprising an attachment hub 36 and an integrally extended semi-cylindrical, or partially cylindrical, body or roller portion 37, are adapted to be rotated in unison with one another and at a constant rate of speed

by means of sprocket gears 38 secured upon the outer extremities of the stub shafts 35, the sprocket gears 38 being connected by sprocket chains 39 to similar sprocket gears 40 upon the outer ends of the shaft 25. Thus it will be seen that these rollers, i. e., the upper and lower rollers, are operatively positioned so as to be rotated in unison inwardly toward the rear of the machine, whereby the blanks upon being positioned within the bight of the rollers will be drawn therebetween one at a time and forced rearwardly a predetermined distance, as will be later explained.

Conventional separator disks 41, mounted upon angularly positioned stub shafts 42 transversely journaled in brackets 43 and through the head at 43^a, are provided atop the machine and are adapted to be driven by horizontal shafts 44 by means of intermediate bevel gears 45, the shafts 44 being continuously driven by gear trains 46 driven by gears 47 on the shaft 35 on either side of the machine. Reciprocatory stop pins 48 actuated by the conventional cam and follower system 49 operate in synchronization with the separator disks, both the separator disks and stop pins serving to separate and retain the unused blanks in the conventional manner, a ratched blank holder 50 being provided for retaining the blanks until drawn downwardly, as will be later explained.

An adjustable "cross" type blank or sheet holder is provided beneath the separator disks for supporting the blanks 51 as fed to the machine. This holder comprises a bottom plate 52 medially and angularly positioned within and parallel to the base frames B, the upper, arcuate end 53 being directed toward the bight of the aforementioned rollers and the lower end being secured to a cross-bar 54, which is in turn secured to the base frames B, a transversely positioned guide arm plate 55 slidably mounted upon the bottom plate, and a pair of guide arms 56 each slidably mounted upon either side of the guide arm plate, each guide arm having a guide pin 57 rigidly secured thereto and extended perpendicularly upwardly therefrom. A horizontal guide strip 58 is extended from the upper, arcuate end of the bottom plate inwardly between the rollers so as to prevent the forward ends 59 of the blanks falling downwardly and away from spacing and conveyor belts on the rearward side of the rollers, the operation and use of which will be later explained. The guide strip 58 is rounded as at 58' at the forwardly extended portion adjacent the rollers 33 and 34. The purpose of this is to bend the sheets transversely as they pass over the guide strip 58, and by this means to prevent sidewise displacement of said sheets. A recess 60 is formed in the lower roller for the reception of the guide strip so that the upper surface of this strip will be flush with the top of the roller. A series of threaded apertures 61 are provided near the upper end of the bottom plate for attaching thereto a suction hose 62 for releasably holding the blanks when the machine is in operation. The suction is continuous during the operation of the machine.

A suction arm 63 rigidly mounted upon a tubular shaft 64 and having an air duct communicating therewith is journaled across the head C, and is adapted to be reciprocated below the stacked blanks 51 so as to intermittently draw the lowermost blank downwardly into the bight of the rollers, the suction for this arm being obtained from any suitable source and connected

thereto by the hose 65 pivotally attached to the tubular shaft 64. The above suction arm shaft is oscillated by a conventional cam and follower system 66 externally positioned upon the far end of the shaft 28, the follower being pivotally connected to the tubular arm by the crank 67.

A sprocket gear 68 is rigidly mounted on the aforementioned power shaft 18 within the frames B and is connected by means of a sprocket chain 69 to a large sprocket gear 70 secured upon a shaft 71 journaled between the side frames B in the horizontal webs D thereof. The shaft 71 has a small spur gear 72 secured thereto adapted to mesh with and drive a relatively larger gear 73 secured upon a stub shaft 74 journaled through one of the adjacent webs D, the gear 73 being also within the side frames B. A "quick change" type gear 75 secured in any conventional manner upon the stub shaft 74 externally of the machine is provided and is adapted to mesh with a mating "quick change" type gear 76 secured upon a shaft 77, the shaft 77 being journaled transversely the frames B through the vertical webs E. This shaft 77 has a small spur gear 78 secured thereon within the frames B at one side thereof. A gear 79, similar to the gear 78 and in mesh therewith, is secured upon a shaft 80, this shaft being depended from the upper part of the side frames by means of hangers 81. Thus it is seen that these spur gears 78—79 are directly driven in opposition to one another by the spur gears 75 and 76, and that the speed of the former may be changed by changing the ratio of the latter gears, the advantage of which will be later shown.

A pair of endless belts 82 are provided upon and about the shaft 77 in a spaced, transverse relationship to one another, and travel upwardly and rearwardly about spaced rollers 83 journaled upon a shaft 84 secured atop the head C at the rear thereof, and travel downwardly about the rear of a drum type roller 85 secured upon a shaft 86, journaled through the head at 87, whereupon the belts continue downwardly and forwardly over a surface plate 88 to the shaft 77, tension pulleys 89 or the like being provided for keeping the belts taut. The aforementioned drum type roller 85 is rotated by means of a large spur gear 90, secured upon the shaft 86 thereof, being driven by a small gear 91 secured upon a shaft 92 journaled across the head. This shaft has a sprocket gear 93 secured upon the outer end thereof externally of the machine, on the operator's side, the said sprocket being connected by means of a sprocket chain 94 to a sprocket gear 95 upon the shaft 77 by means of which this system, that is, the drum roller 85, is operated at the same surface speed as the shafts 77—80, the shafts 77—80 being regarded as rollers. A similar pair of endless belts 96 is provided about the shaft 80, as shown in Fig. 3, the path of travel being upwardly over the surface plate 88 atop the belts 82, about the drum roller 85 beneath the belts 82, upwardly over the drum onto a bed plate 97, forwardly over a roller 98 journaled upon a shaft 99, and downwardly about the shaft 80, an idler roller 100 being provided for keeping the belts taut. A central endless belt 101 is provided about the drum roller 85, the forward roller 98 and an idler roller 102 for assisting the belts 96 as will be later shown. Thus by this arrangement the belts 82—96, 101 are driven toward each other at the same rate of speed, the speed of which may be varied by changing the ratio of the gears 75—76.

A spacing or calibrating mechanism 103 is pro-

vided atop the bed plate 97 upon the belt 101, for spacing the blanks as they pass therebetween. This spacing mechanism consists of a forked arm holder 103 pivotally and medially mounted upon the shaft 84 by means of the apertured forks 104, the juncture of the forks or body portion 105 having a bore 106 extended therethrough for the reception of the forwardly extended spacing arm 107, a cap screw 108 being provided for securing the arm therein. A spacing roller carriage 109, somewhat similar in appearance to the forked armholder, is slidably positioned upon the arm 107 by virtue of a bore 110 extended through the body portion 111 thereof, a wing bolt 112 being provided for releasably securing the carriage to the arm 107. A pair of rollers 113 are rotatably mounted within a pair of forks 114 depended from the body portion 111 of the carriage and are adapted to ride upon the central endless belt 101 until the blanks 51 come in contact therewith, whereupon the blanks intermittently pass thereunder, this being the point at which the blanks are spaced to expose the desired amount of surface. A guide strip 115 of such width, as to permit it to be nicely yet freely positioned between the spacing rollers 113 is provided and is extended forwardly to and between the spaced segmental rollers 34 and in horizontal alignment with the bight thereof for guiding the blanks beneath the spacing rollers, the forward portion 116 being curved upwardly for this purpose, there being a slot 117 formed therein for the reception of the suction arm on its downward stroke. This guide strip has an upwardly extended pin 118 for insertion into a holder 119, a cap screw 120 being provided for securing the pin therein. The holder 119 has a bore 121 extended therethrough by means of which it is positioned upon the arm 107, a cap screw 122 being provided therein for securing it upon the arm.

A coiled expansion spring 123 has its upper end positioned in a recess or niche 124 in the rearward underside of the body portion 106 of the forked arm holder 103, and has its lower end positioned over a pin 125 integrally formed with a spring holder 126, the said spring holder being immovably secured to the shaft 84, within the formed arm holder, by means of a cap screw 127. The normal action of this spring tends to force the spacing rollers and guide strip downwardly upon the belt 101, thereby assuring a perfect spacing of the overlapped blanks.

In the operation of this device, the blanks to be fed to the machine, and spaced in a superposed order, are evenly and orderly stacked upon the blank holder, whereupon the guide pins 57 are adjusted so as to hold the blanks snugly yet releasably against the ratchet blank holder 50. The spacing roller carriage is then moved forwardly or backwardly upon the spacing arm according to the length of the blanks to be fed to the machine, and the positioning of these spacing rollers may be done by calibrating the spacing arm or by trial and error. Next the correct set or pair of segmental feed rollers are selected, and secured upon their respective shafts, thereby determining the intermittent travel of the blanks between the feed rollers. Finally the correct set of spacing gears (gears 75 and 76) are selected and secured upon their respective shafts, thereby governing the speed of the conveyor or endless belts. After these adjustments have been made, the machine is set in operation whereupon the oscillatory suction arm seizes the lowermost blank and pulls it downwardly through the rotating sep-

arator disks into the bight of the upper segmental rollers 34 and the lower cylindrical roller 33. Upon being drawn downwardly into the bight of these rollers, the blank is pulled down onto the bottom blank holder plate 52 where it is slidably retained by virtue of the continuous suction maintained thereat by the hose 62 connected thereto. As the blank is drawn into the rollers it is forced forwardly by the frictional contact of the rollers rotating inwardly toward one another away from the stacked blanks. In the meantime the suction arm has returned to its upward position, thereby completing a cycle of operation. As the blanks are intermittently discharged from the continuously rotating feed rollers, they are forced between the guide strip 115 of the spacing mechanism and the rearwardly moving endless belts by means of which the first blank is carried into contact with the spacing rollers 113, at which point the blank definitely assumes the speed of the endless belts therebelow, the spacing rollers holding the blank in firm contact therewith. Inasmuch as the endless belts are moving at a slower rate of speed relative to the feed rollers, the blanks assume a definite and constant superposed relationship to one another, which is maintained by additional conveyor belts until it is no longer desirable.

Figs. 10 and 11 show a modified form of hose connection for the bottom plate of the blank holder.

As shown in Fig. 13, a modified type of adjustable, segmental roller is shown that is intended to replace the aforementioned fixed type of segmental roller when the feeding and spacing machine is to be used in connection with blanks or sheets having window apertures of varying depths, which are difficult to withdraw from the pile if the advancing segment is deep enough to withdraw the blanks a greater space than slightly less than the depth of the aperture of the window. This leads to the adoption of a series of easily removable and replaceable plates of different depths adapted to draw out the window blanks slightly less than the depth of the window aperture. The calibration and holding down of the sheets is preferably accomplished in my modified method by additional suction holes provided to hold down the spaced-out blanks, the vacuum holes being placed in relation to the spaced-out blanks so that the vacuum will be exerted against the exposed rear edge underportion of each exposed sheet.

The adjustable segmental roller 129 consists of a body portion 130, similar in shape to that of the fixed segmental roller, upon which is secured by screws 131 or the like a plate 132 of the same radius of curvature as the body portion, various sized plates being provided so that the depth of the segment is less than the depth of the window aperture in the blank being fed through my device, in order to prevent the catching of the rear edge of the window aperture of the blank being advanced against the forward edge of the window aperture of the blank in advance of and beneath the blank being advanced by the segmental rollers.

By the mechanism which I have set forth and described above, I am enabled to maintain an exact longitudinal alinement of the advancing overlapped sheets in a true rotary manner, as distinguished from the start and stop movement of the reciprocator or Geneva type, whereby I provide a simple machine and increase the productive capacity thereof. As the longitudinal alinement is always exact, as well as the spacing

of the sheets, it preserves the proper synchronization of the spacing unit with the folding or other succeeding units.

I claim:

5. In combination, means for supporting a stack of blanks, roller segment mechanism comprising a roller segment and a roller opposed thereto for intermittently engaging and advancing blanks step by step from said stack, sucker mechanism for introducing the blanks from said stack between said roller and roller segment, said roller segment having a circumferential extent smaller than the shortest sheet of said stack so that said sheets are advanced by said roller segment mechanism in overlapping relation, subsequently acting mechanism for engaging and advancing each blank only after it has been advanced through a plurality of steps by the roller segment, and means for engaging said blanks 10 after they are disengaged from the stack and before they reach the subsequently acting mechanism to hold stationary between the roller and roller segment, during the periods when the roller segment is not in position to co-act with the roller, sheets which would otherwise be uncontrollable in such periods.
15. In combination, means for supporting a stack of blanks, roller segment mechanism comprising a roller segment and a roller opposed thereto for intermittently gripping blanks and advancing them from said stack, picker mechanism for successively introducing the blanks from the stack between the roller and the roller segment, said roller segment having a circumferential extent smaller than the shortest blank of 20 said stack so that said blanks are advanced by said roller segment mechanism step by step in overlapping relation, and suction means for gripping the exposed trailing margin of a blank which has been advanced by the roller segment mechanism, but which still requires to be advanced by such mechanism in order to be moved clear thereof, to hold such blank against shifting during a period when the roller segment runs out of coacting relation with the roller.
25. In combination, means for supporting a stack of blanks, roller segment mechanism comprising a roller segment and a roller opposed thereto for intermittently gripping blanks and advancing them from said stack, picker mechanism for successively introducing the blanks from the stack between the roller and the roller segment, said roller segment having a circumferential extent smaller than the shortest blank of 30 said stack so that said blanks are advanced by said roller segment mechanism step by step in overlapping relation, and means for yieldingly gripping a blank which has been disengaged from the stack and which has been advanced by the roller segment mechanism, but which still requires to be advanced by such mechanism in order to be moved clear thereof, to hold such blank against shifting during a period when the roller segment runs out of coacting relation with the roller.
35. In combination, means for supporting a stack of blanks, roller segment mechanism comprising a roller segment and a roller opposed thereto for intermittently gripping blanks and advancing them from said stack, picker mechanism for successively introducing the blanks from the stack between the roller and the roller segment, said roller segment having a circumferential extent smaller than the shortest blank of 40 said stack so that said blanks are advanced by said roller segment mechanism step by step in overlapping relation, and suction means for gripping the exposed trailing margin of a blank which has been advanced by the roller segment mechanism, but which still requires to be advanced by such mechanism in order to be moved clear thereof, to hold such blank against shifting during a period when the roller segment runs out of coacting relation with the roller.
45. In combination, means for supporting a stack of blanks, roller segment mechanism comprising a roller segment and a roller opposed thereto for intermittently gripping blanks and advancing them from said stack, picker mechanism for successively introducing the blanks from the stack between the roller and the roller segment, said roller segment having a circumferential extent smaller than the shortest blank of 50 said stack so that said blanks are advanced by said roller segment mechanism step by step in overlapping relation, and means for yieldingly gripping a blank which has been disengaged from the stack and which has been advanced by the roller segment mechanism, but which still requires to be advanced by such mechanism in order to be moved clear thereof, to hold such blank against shifting during a period when the roller segment runs out of coacting relation with the roller.
55. In combination, means for supporting a stack of blanks, roller segment mechanism comprising a roller segment and a roller opposed thereto for intermittently gripping blanks and advancing them from said stack, picker mechanism for successively introducing the blanks from the stack between the roller and the roller segment, said roller segment having a circumferential extent smaller than the shortest blank of 60 said stack so that said blanks are advanced by said roller segment mechanism step by step in overlapping relation, and means for yieldingly gripping a blank which has been disengaged from the stack and which has been advanced by the roller segment mechanism, but which still requires to be advanced by such mechanism in order to be moved clear thereof, to hold such blank against shifting during a period when the roller segment runs out of coacting relation with the roller.
65. In combination, means for supporting a stack of blanks, roller segment mechanism comprising a roller segment and a roller opposed thereto for intermittently engaging and advancing blanks from said stack between said roller and roller segment, said roller segment having a circumferential extent smaller than the shortest sheet of said stack so that said sheets are advanced by said roller segment mechanism in overlapping relation, and suction means for engaging
70. In combination, means for supporting a stack of blanks, roller segment mechanism comprising a roller segment and a roller opposed thereto for intermittently engaging and advancing blanks from said stack between said roller and roller segment, said roller segment having a circumferential extent smaller than the shortest sheet of said stack so that said sheets are advanced by said roller segment mechanism in overlapping relation, and suction means for engaging
75. In combination, means for supporting a stack of blanks, roller segment mechanism comprising a roller segment and a roller opposed thereto for intermittently engaging and advancing blanks from said stack between said roller and roller segment, said roller segment having a circumferential extent smaller than the shortest sheet of said stack so that said sheets are advanced by said roller segment mechanism in overlapping relation, and suction means for engaging

said blanks at a point between said stack and said roller segment mechanism to hold a blank against disarrangement between the roller and roller segment, during a period of non-engagement therewith of the roller segment.

5. In combination, means for supporting a stack of blanks, mechanism comprising a roller segment for intermittently engaging the blanks and advancing them step by step in overlapping relation, subsequent blank feeding mechanism for taking over control of the overlapped blanks from the roller segment mechanism, and suction means for engaging a blank which extends through said roller segment mechanism and which has not yet passed into the control of the subsequent feeding mechanism, to retain said blank against disarrangement during an interval when it is not engaged by the roller segment mechanism.

6. In combination, means for supporting a stack of blanks, mechanism comprising a roller segment for advancing blanks from said stack in overlapping relationship, forwarding means beyond said roller segment mechanism, said forwarding means operating at a lesser speed than that of said roller segment mechanism, and means for adjusting said forwarding mechanism in position so as to cause it to align and take over control of each blank of the advancing band at an instant just prior to the conclusion of the final advance thereof by said roller segment mechanism.

7. In a sheet-spacing mechanism, a sheet holder for releasably holding stacked sheets, means for advancing in overlapped position sheets in spaced relationship to each other, segmental feed rollers positioned upon and in alignment with a lower cylindrical roller, means for continuously rotating said rollers, means for positioning sheets into the bight of the said rollers, means for advancing a plurality of sheets forwardly a predetermined distance while said sheets are retained in exact longitudinal alignment, and a mechanism for continuing the advancement of said sheets the instant said sheets are released from said rollers comprising a spacing arm, a spacing roller secured upon said arm and adapted to ride upon the spaced blanks, a continuously travelling belt located beneath the spaced blanks, a bed plate over which the belt travels, means for driving said belt, and means for changing the speed of travel of said belt.

8. In a sheet-spacing mechanism, a sheet holder for releasably holding stacked sheets, means for advancing in overlapped position sheets in spaced relationship to each other, segmental feed rollers positioned upon and in alignment with a lower cylindrical roller, means for continuously rotating said rollers, means for positioning sheets into the bight of the said rollers, means for advancing a plurality of sheets forwardly a predetermined distance while said sheets are retained in exact longitudinal alignment, and a mechanism for continuing the advancement of said sheets the instant said sheets are released from said rollers comprising a spacing arm, a spacing roller slidably secured upon the spacing arm and adapted to ride upon the spaced blanks, a continuously travelling belt located beneath the spaced blanks, a bed plate over which the belt travels, means for driving said belt, and means for changing the speed of travel of said belt.

9. In a sheet-spacing mechanism, a sheet holder for releasably holding stacked sheets, means for advancing in overlapped position

sheets in spaced relationship to each other, said means comprising a suction member for seizing and moving the lowermost of said stacked sheets, segmental feed rollers positioned upon and in alignment with a lower cylindrical roller, means for continuously rotating said rollers, means for positioning sheets into the bight of said rollers, means for advancing a plurality of sheets forwardly a predetermined distance while said sheets are retained in exact longitudinal alignment, and a mechanism for continuing the advancement of said sheets the instant said sheets are released from said rollers comprising a spacing arm and a spacing roller secured upon the spacing arm and adapted to ride upon the spaced blanks, a continuously travelling belt located beneath the spaced blanks, a bed plate over which the belt travels, means for driving said belt, and means for changing the speed of travel of said belt.

10. In a sheet-spacing mechanism, a sheet holder for releasably holding stacked sheets, means for advancing in overlapped position sheets in spaced relationship to each other, said means comprising a reciprocating suction arm for seizing and moving the lowermost of said stacked sheets, segmental feed rollers positioned upon and in alignment with a lower cylindrical roller, means for continuously rotating said rollers, means for positioning sheets into the bight of said rollers, means for advancing a plurality of sheets forwardly a predetermined distance while said sheets are retained in exact longitudinal alignment, and a mechanism for continuing the advancement of said sheets the instant said sheets are released from said rollers comprising a spacing arm, a spacing roller secured upon the spacing arm and adapted to ride upon the spaced blanks, a continuously travelling belt located beneath the spaced blanks, a bed plate over which the belt travels, means for driving said belt, and means for changing the speed of travel of said belt.

11. In a sheet-spacing mechanism, a sheet holder for releasably holding stacked sheets, means for advancing in overlapped position sheets in spaced relationship to each other, said means comprising a reciprocating suction arm for seizing and moving the lowermost of said stacked sheets, segmental feed rollers positioned upon and in alignment with a lower cylindrical roller, means for continuously rotating said rollers, means for transversely arching the sheets advancing into the bight of the said rollers, means for advancing a plurality of sheets forwardly a predetermined distance while said sheets are retained in exact longitudinal alignment, and a mechanism for continuing the advancement of said sheets the instant said sheets are released from said rollers comprising a spacing arm, a spacing roller secured upon the spacing arm and adapted to ride upon the spaced blanks, a continuously traveling belt located beneath the spaced blanks, a bed plate over which the belt travels, means for driving said belt, and means for changing the speed of travel of said belt.

12. In a sheet-spacing mechanism, a sheet holder for releasably holding stacked sheets, means for advancing in overlapped position sheets in spaced relationship to each other, said means comprising a reciprocating suction arm for seizing and moving the lowermost of said stacked sheets, vacuum means for holding each sheet when released from the sheet holder, seg-

mental feed rollers positioned upon and in alignment with a lower cylindrical roller, means for continuously rotating said rollers, means for positioning the sheets into the bight of said rollers, means for advancing a plurality of sheets forwardly a predetermined distance while said sheets are retained in exact longitudinal alignment, said means being stronger than said vacuum holding means, and a mechanism for continuing the advancement of said sheets the instant said sheets are released from said rollers comprising a spacing arm, a spacing roller secured upon the spacing arm and adapted to ride upon the spaced blanks, a continuously travelling belt located beneath the spaced blanks, a bed plate over which the belt travels, means for driving said belt, and means for changing the speed of travel of said belt.

13. In an apparatus for arranging and advancing sheets in fanned out relation, in combination, a support for a stack of sheets, roller mechanism comprising opposed rotary members for intermittently gripping sheets between them to advance the sheets step by step, means for periodically placing the leading margins of the sheets from the stack one after another in the space between the rotary members, subsequently acting mechanism for engaging and advancing each sheet only after it has been advanced through a plurality of steps by the roller mechanism, and means for holding stationary during a period when the rotary members are out of sheet gripping relation to one another, a partially advanced sheet between the rotary members which has become disengaged from the stack and which would otherwise be uncontrolled in such period.

14. In an apparatus for arranging and advancing sheets in fanned out relation, in combination, a support for a stack of sheets, roller segment mechanism comprising roller segment means and roller means opposed thereto for intermittently gripping the sheets and advancing them step by step through steps equal in extent to only a fraction of a sheet length, means for

periodically introducing the leading margins of sheets from the stack one after another between the roller segment means and the roller means, subsequently acting mechanism for engaging and advancing each sheet only after it has been advanced through a plurality of steps by the roller segment mechanism, and means for gripping a sheet which has been advanced by the roller segment mechanism, but which still requires to be advanced by such mechanism in order to be moved clear thereof, to hold stationary during a period when the roller segment means runs out of sheet gripping relation with the roller means, such sheet after it has become disengaged from the stack so that it would otherwise be uncontrolled in such period.

15. In an apparatus for arranging and advancing sheets in fanned out relation, in combination, a support for a stack of sheets, roller segment mechanism comprising roller segment means and roller means opposed thereto for intermittently gripping the sheets and advancing them step by step through steps equal in extent to only a fraction of a sheet length, means for periodically introducing the leading margins of sheets from the stack one after another between the roller segment means and the roller means, constantly running mechanism for engaging each sheet only after it has been advanced through a plurality of steps by the roller segment mechanism, and advancing it continuously in fanned out relation with the sheets which have preceded it, means for gripping a sheet which has been advanced by the roller segment mechanism, but which still requires to be advanced by such mechanism in order to be moved clear thereof, to hold stationary, during a period when the roller segment means runs out of sheet gripping relation with the roller means, such sheet after it has become disengaged from the stack so that it would otherwise be uncontrolled in such period.

CHARLES F. PFLANZE.
